UNITED STATES PATENT OFFICE.

PAUL STEIFF, OF GIENGEN-ON-THE-BRENZ, GERMANY, ASSIGNOR TO MARGARETE STEIFF, INC., OF NEW YORK, N. Y., A CORPORATION OF NEW YORK.

DESIGN FOR A STUFFED TOY ANIMAL OR SIMILAR ARTICLE OF MANUFACTURE.

Application filed October 28, 1928. Serial No. 28,657. Term of patent 7 years.

To all whom it may concern:

Be it known that I, PAUL STEIFF, a citizen of Germany, residing at Kurzestr. 1, Giengen-on-the-Brenz, Wurttemberg, Germany, have invented a new, original, and ornamental Design for a Stuffed Toy Animal or Similar Article of Manufacture, of which the following is a specification, reference being had to the accompanying drawing, forming a part thereof, in which—

Fig. 1 is a side view of a stuffed toy animal or similar article of manufacture, showing my new design; and Fig. 2 is a face view of the same.

I claim:

The ornamental design for a stuffed toy animal, or similar article of manufacture, substantially as shown.

PAUL STEIFF.
